UNITED STATES PATENT OFFICE

WILLIAM J. H. RUSCHMEYER, OF TOLEDO, OHIO

BUILDING

Application filed March 3, 1930. Serial No. 432,780.

This invention relates to buildings and more particularly to an improvement in a building used for banking and other similar businesses where money, securities and other objects of value are stored.

One object of the invention is to provide a building in which it is necessary to pass through a number of rooms or chambers in order to reach a vault wherein money and other objects of value are stored for safe keeping, and provide an improved arrangement of doors normally retained opened and adapted to drop to closed positions when the protecting apparatus is in operation.

Another object of the invention is to cause doors guarding an entrance to an outer chamber to be released and caused to drop to closed positions when an intruder first enters a compartment directly in front of the vault and then cause a door guarding the entrance to the chamber immediately in front of the vault to be closed if the intruder continues his approach toward the vault.

Another object of the invention is to not only cause the doors to be released for movement into closed position, but to so arrange the compartment or chamber immediately in front of the vault that the entire compartment will drop downwardly through a shaft similar to an elevator shaft if the intruder continues to approach the entrance to the vault after the doors guarding the outer chamber have been released and dropped to a closed position.

Another object of the invention is to so construct mechanism controlling the doors that during working hours releasing of the doors will be prevented and thereby employees of the bank permitted to approach the safe without danger of the safety doors dropping.

Another object of the invention is to so install the movable chamber immediately in front of the vault entrance that it may be guided in its vertical movement through a shaft resembling an elevator shaft and moved upwardly therein to its normal position after being dropped by mechanism similar to that controlling movement of an elevator car in its shaft.

Another object of the invention is to prevent damage to the doors and movable compartments when they are released and allowed to drop.

Another object of the invention is to provide means whereby movement of cables attached to the outer doors may be guided when the cables are released and the doors moved downwardly, and thereby prevent the cables from becoming tangled and preventing the doors from entirely closing.

The invention is illustrated in the accompanying drawings, wherein

Fig. 1 is a sectional view through a portion of a bank building, taken along the line 1—1 of Fig. 5, and showing the movable compartment and other mechanism in elevation.

Fig. 2 is a vertical sectional view taken along the line 2—2 of Fig. 5 with the safety doors raised and the floor of the movable compartment in a normal position.

Fig. 3 is a view similar to Fig. 2 showing the movable floor of the movable compartment tilted in one direction to release the outer doors which are shown closed.

Fig. 4 is a view showing the floor of the movable compartment tilted in an opposite direction from that shown in Fig. 3, and the inner door closed and the movable compartment at the bottom of the shaft in a sub-chamber of the building.

Fig. 5 is a vertical sectional view taken along the line 5—5 of Fig. 2, showing the movable chamber in its normal position.

Fig. 6 is a vertical sectional view taken along the line 6—6 of Fig. 2 and looking toward the outer doors.

Fig. 7 is a horizontal sectional view taken along the line 7—7 of Fig. 2.

Fig. 8 is a horizontal sectional view taken along the line 8—8 of Fig. 2.

Fig. 9 is a perspective view of the inner safety door.

The building, which is indicated in general by the numeral 1, represents a portion of a bank building or other building in which valuable objects are stored, and the main entrance chamber or lobby of this building is indicated by the numeral 2. The building may be of any height desired and

back of the chamber 2 is located a vault 3 having doors 4 which may be of any construction desired, and equipped with locking means including dials 5. This vault is separated from the chamber 2 by a shaft 6 which extends vertically in the building and has its upper end opening into a chamber 7 and its lower end opening into a chamber 8 which extends beneath the chamber 2.

10 A chamber 9 which resembles an elevator car and may be referred to as a movable chamber is mounted in the shaft 6 to slide vertically therein and from the top of this chamber rises a frame 10 including a cross bar 11 to which is secured a cable 12 similar to the cables usually attached to elevator cars. This cable will be wound upon a drum of hoisting mechanism (not shown) and within the chamber is mounted a control 13 of a conventional construction so that when the chamber has been dropped to the bottom of the shaft it may be moved upwardly and restored to its normal position shown in Fig. 2. It will be understood 15 that the hoisting mechanism will be rendered inoperative at night so that a burglar standing in the movable compartment when it drops to the bottom of the shaft will be prevented from actuating the control 13 and 20 restoring the movable compartment to its normal position. This compartment is open at its front and back so that under normal conditions, an employee of the bank may pass through the compartment and by opening 25 the doors 4 open the safe or vault.

If a burglar opens the door or doors 14 mounted at the outer entrance 15 of the chamber 2 and approaches the vault with the intention of robbing the bank, it is desired 30 to confine the burglar within the building, and in order to do so, there have been provided doors 16 which are normally disposed in pockets 17 and adapted to move downwardly through tracks 18 into closing relation to the entrance 15.

35 Dash pots 19 are mounted in the subchamber 8 with their plungers 20 extending upwardly through the floor 21 into the lower ends of the tracks so that when the doors drop they will strike the plungers and thereby prevent the doors from being broken or otherwise damaged by the fall.

Ordinarily the doors 16 are to be retained in an elevated position within the pocket 17 40 and in order to do so there have been provided cables 22 which are attached to eyes 23 carried by the doors. These cables extend upwardly and are engaged over guide pulleys 24 mounted in brackets 25 rising 45 from the floor of the compartment or chamber 7, and after being engaged with the guide pulleys, the cables are extended horizontally through guide troughs 26 disposed horizontally and supported upon struts 27. 50 These troughs diverge towards the shaft and

their rear ends, which are enlarged to form mouths 28, are disposed adjacent opposite sides of the shaft, as clearly shown in Fig. 5. It will thus be seen that hooks 29 provided at the upper rear ends of the cables 70 may be engaged with lips 30 at the upper ends of tubes 31 mounted vertically in the shaft against the side walls thereof at opposite sides of the movable compartment, as shown in Fig. 7.

75 The entrance 32 between the chamber 2 and the movable compartment or chamber 9 is also to be guarded, and in order to do so, there has been provided a door 33 of an ordinary construction, and a protecting door 34 80 which is slidably mounted at the opposite side of the partition 35 from the door 33, and movable through guides 36 from the raised position shown in Fig. 2, to the closed position shown in Fig. 4. Arms 37 project 85 from the door 34 to rest upon the top of the movable chamber and therefore when the movable chamber drops to the bottom of the shaft the door will move downwardly with it to a closed position, and when the movable chamber is hoisted and returned to its 90 normal position, the door will be again raised.

95 In order to allow the movable chamber to be releasably secured in a raised position, and assist the return thereof to a raised position after being dropped, there have been provided weights 38 slidably mounted in vertically disposed pockets 39 and having their upper ends secured to cables 40 which extend upwardly into the chamber 7 and are engaged with guide pulleys 41 carried by brackets 42. These cables extend downwardly into the shaft and are secured about the bar 11 adjacent opposite sides of the frame 10. It will 105 thus be seen that the weights 38 will slide vertically in the pockets 39 when the movable chamber 9 moves in the shaft, but will travel in an opposite direction to the direction of the movable chamber.

110 Latches 43 extend vertically in slots 44 formed in the pockets and are pivotally mounted as shown at 45 with their lower ends extending downwardly into the chamber 8 and terminating in arms 46 which project towards the shaft. At their upper ends the latches are formed with bills 47 projecting inwardly and adapted to engage over the weights 38 to normally prevent upward movement of the weights and retain the movable chamber in its normal position. It will be noted that the upper faces of these bills are curved so that as the weights move downwardly, the latches may be swung outwardly and thereby allow the weights to move 120 downwardly to their proper position for engagement by the bills when the movable chamber is raised.

125 Releasing of the hooks 29 and movement of the latches to release the weights, is to be 130

effective by the weight of a person standing within the movable compartment. In order that this may take place, the floor 48 of the movable compartment is formed separately from the side walls thereof and across the under face of the floor is secured a fulcrum bar 49. This fulcrum bar projects from opposite sides of the floor and has rounded or circular portions 50 constituting trunnions which are rotatably received in bearings 51 firmly secured to the side walls of the movable member. A bracing strip 52 extends below the fulcrum bar and has its ends secured to the lower ends of the bearings. This strip, not only serves to brace the bearings, but also constitutes a bumper adapted to strike the plunger 53 of a dash pot 54, provided at the bottom of the shaft in order to absorb shocks and prevent damage to the movable compartment when it drops to the bottom of the shaft.

Under normal conditions, the floor is to be held stationary in a horizontal position, and in order to do so there have been provided locking strips 55 which are slidably mounted in pockets 56 extending vertically in the shaft at opposite sides of the movable chamber. These locking strips have their lower ends formed with forks 57 between which tongues 58 at the ends of the fulcrum bar are to be engaged, and it will be readily understood from an inspection of Figs. 1 and 5 that when the locking strips are lowered, for engagement with the tongues, it will be impossible for the fulcrum bar to turn in the bearings. These locking strips have racks 59 formed along the rear edges of their upper portions for engagement by pinions 60 fixed upon a shaft 61 mounted in bearings at the upper ends of standards 62, and intermediate the length, the shaft carries a handwheel 63 in order that it may be rotated and the locking strips shifted vertically. Therefore, by rotating the shaft in the proper direction the strips may be moved upwardly out of engagement with the tongues, as shown in Fig. 3, and the floor of the movable chamber will be free to tilt out of a vertical position to either the tilted position shown in Fig. 3, or that shown in Fig. 4.

As previously stated, the hooks 29 and weights 38 are to be released according to the direction in which the floor of the movable chamber tilts and in order to do so, the floor has secured against its under face abutment arms 64 which project from opposite sides of the floor below the lower ends of the tubes or pockets 31, and other arms 65 which project forwardly into position to engage the arms 46 of the latches 43. Side arms 66 extend from the arms 65 and are adapted to engage beneath the side walls of the movable chamber and limit tilting movement of its floor in one direction. Rods 67 are slidably mounted in the pockets 31 and are of such

length that when they are engaged by the arms 64 and moved upwardly thereby, their upper ends will engage the bills of the hooks 29 and force these hooks upwardly out of engagement with the keepers or tongues 30 rising from the upper ends of the pockets. It will thus be seen that when the floor of the movable chamber is tilted in one direction, the rods 67 will be shifted upwardly to release the hooks 29 and allow the doors 16 to drop to a closed position in guarding relating to the entrance 15, and that when the floor is tilted in an opposite direction the latches 43 will be released to move the weights and allow the movable chamber to drop to the bottom of the shaft within the compartment 8 during which movement the door 34 will follow the movable chamber downwardly into guarding relation to the doorway 32.

When a bank building is constructed in accordance with this invention, it is necessary to pass through the movable compartment in order to reach the vault. During the day time the securing strips 55 are in a lowered position and since they engage the tongues 90 projecting from the fulcrum bar, the floor will be held stationary.

At night time, and on Sundays and holidays when a bank is closed, it is desired to prevent a burglar or other unauthorized person from having access to the vault. Therefore, at closing time, an employee of the bank enters the chamber 7 and by rotating the shaft 61 through the medium of its hand wheel raises the securing strips, as shown in Fig. 3, so that their forks no longer engage the tongues at the ends of the fulcrum bar. This sets the safety mechanism in position for operation.

If a burglar succeeds in opening the doors 14 or by any other method enters the chamber 2, and then opens the doors 33, it is necessary for him to pass through the compartment 9 in order to reach the vault. As soon as the intruder steps upon the floor 48, which is now permitted to tilt, the pressure will swing the forward end portion of this floor downwardly until such movement is stopped by the arms 64 striking the lower ends of the rods 67 and forcing the rods upwardly. As the rods move upwardly, their upper ends engage the bills of the hooks 29 to move them out of engagement with the keepers 30 and this releases the hooks and allows the cables 22 to slide through the troughs 26, and the doors 16 to move downwardly into closing relation to the entrance or doorway 15.

This may alarm the burglar, but if he does not immediately leave the bank building by some other means than the doorway 15, it is still necessary for him to walk across the floor in order to reach the vault. In doing so the burglar walks past the fulcrum bar and this causes the floor to tilt in an opposite direction until the arms 65 strike the arms 46 of

the latches 43. This causes the latches to be swung to the position shown in Fig. 4, and their bills 47 are moved out of engagement with the upper ends of the weights 38. Therefore, the weights will be released for upward movement and the movable chamber will drop downwardly in the shaft until it enters the compartment or subchamber 8 and rests at the bottom of the shaft upon the dash pot of shock absorber 54. As the movable chamber descends the door 34 will slide downwardly with it, thereby closing the doorway 32. This door 34 is very heavy and it will be impossible for a burglar to escape even if he should, in some way, manage to break his way through the top of the movable compartment. Therefore, the burglar will be confined in the subchamber until police arrive. Access to the subchamber by police or other proper authorities may be had through a suitable entrance, the door of which will be locked upon the outside so that it cannot be opened by a burglar confined in a subchamber. After the burglar has been removed from the subchamber, a switch controlling operation of the hoisting mechanism is closed and an employee of the bank may then actuate the control 13 and cause the movable chamber to travel upwardly and return to its normal position. During the movement the door 34 will be returned to the raised position by pressure of the movable chamber against the arms 37. The cables 22 may then be grasped by a number of persons in order to raise the doors 16, or these cables may be drawn upwardly by means of a suitable windlass, until the hooks 29 may be again engaged with the tongues 30. Before the doors 16 are raised, the shaft 61 will be rotated in order to move the securing strips downwardly for engagement with the tongues of the fulcrum bar in order to secure the floor in a horizontal position. The mechanism will now be restored to its original position and the vault may be safely approached by authorized persons.

What I claim is:—

1. In a bank building, an entrance chamber having a doorway, a strong room, a subchamber, a vertical shaft between said entrance chamber and strong room extending downwardly into said subchamber, a doorway being provided between the shaft and entrance chamber, doors movable into and out of closing relation to said doorways, a chamber movable in said shaft from a normal position, establishing communication between the entrance chamber and strong room to a lowered position within the subchamber, means to releasably retain the door for the entrance chamber opened, means to retain the door of said shaft opened when the movable chamber is in its normal position, means to releasably secure the movable chamber in its normal position, means carried by the mov-

able chamber to release the first door and movable chamber and permit movement of the movable chamber to a lowered position and closing the doors, and means to render the releasing means inoperative. 70

2. In a bank building, an entrance chamber having a doorway, a strong room, a subchamber, a vertical shaft between said entrance chamber and strong room extending downwardly into said subchamber, a doorway being provided between the shaft and entrance chamber, doors movable into and out of closing relation to said doorways, a chamber movable in said shaft from a normal position establishing communication between the entrance chamber and strong room to a lowered position within the subchamber, means to releasably retain the door for the entrance chamber opened, means to retain the door of said shaft opened when the movable chamber is in its normal position, means to releasably secure the movable chamber in its normal position, the floor of said movable chamber being pivoted intermediate its front and rear ends, means to releasably secure the floor against tilting movement, means to release the door for the doorway of the entrance chamber when the floor is tilted in one direction, and means to release the movable chamber when the floor is tilted in an opposite direction. 75 80 85 90 95

3. In a bank building, an entrance chamber having a doorway, a strong room, a vertical shaft between said entrance chamber and strong room extending below the entrance chamber and strong room and having a doorway opening into said entrance chamber, doors for said doorways slidably from a raised position above the doorways to a lowered closed position, a chamber movable in said shaft from a normal position establishing communication between the entrance chamber and strong room to a lowered position at the bottom of the shaft, means to releasably retain the door for the entrance chamber opened, means to releasably secure the movable chamber in its normal position, the door for the shaft entrance being engaged with said movable chamber and moving to a closed position when the movable chamber descends, 100 105 110 115 means actuated by a person entering the movable chamber for releasing the movable chamber, and means to render the releasing means inoperative. 120

4. In a bank building, an entrance chamber having a doorway, a strong room, a vertical shaft between said entrance chamber and strong room extending below the entrance chamber and strong room and having a doorway opening into said entrance chamber, doors for said doorways slidably from a raised position above the doorways to a lowered closed position, a chamber movable in said shaft from a normal position establishing communication between the entrance 125 130

- chamber and strong room to a lowered position at the bottom of the shaft, the door for the shaft entrance resting upon the movable chamber and moving therewith to a closed position when the movable chamber is lowered, the floor of said movable chamber being pivotally mounted, and means actuated by movement of the floor to release the movable chamber and door for the entrance chamber. 5. In a bank building, an entrance chamber having a doorway, a strong room, a vertical shaft between said entrance chamber and strong room, extending downwardly below the same and having a doorway opening into the entrance chamber, a chamber movable in said shaft from a normal position establishing communication between the entrance chamber and strong room to a lowered position below the same, a door for the shaft entrance resting upon the movable chamber and moving downwardly to a closed position when the movable chamber is lowered, weights slidable in vertical tracks at opposite sides of the shaft entrance, cables connecting the weights and movable chamber and trained over guides above the shaft, latches movably mounted and engageable with the weights to retain the movable chamber in its normal position, doors for the doorway of the entrance chamber slidable from a raised to a closed position, cables extending upwardly from the doors for the entrance chamber and engaged with guides and extending horizontally over the shaft and carrying hooks at their ends, means engageable by said hooks to retain the doors raised, and means to release said latches and hooks adapted to be actuated by a person entering the movable chamber. 6. In a bank building, an entrance chamber having a doorway, a strong room, a vertical shaft between said entrance chamber and strong room, extending downwardly below the same and having a doorway opening into the entrance chamber, a chamber movable in said shaft from a normal position establishing communication between the entrance chamber and strong room to a lowered position below the same, a door for the shaft entrance resting upon the movable chamber and moving downwardly to a closed position when the movable chamber is lowered, weights slidable in vertical tracks at opposite sides of the shaft entrance, cables connecting the weights and movable chamber and trained over guides above the shaft, doors for the doorway of the entrance chamber slidable from a raised to a closed position, cables extending upwardly from the doors for the entrance chamber and engaged with guides and extending horizontally over the shaft and carrying hooks at their ends, latches to engage said weights and retain the movable chamber in its normal position, troughs extending horizontally above said shaft to guide movements of the last mentioned cables, tubes extending vertically in said shaft and having stops at their upper ends for engagement by said hooks, plungers slidable in said tubes, and means to move the latches and plunger and release the hooks and weights adapted to the weight of a person entering the movable chamber. 8. In a bank building, an entrance chamber having a doorway, a strong room, a vertical shaft between said entrance chamber and strong room, extending downwardly below the same and having a doorway opening into the entrance chamber, a chamber movable in said shaft from a normal position establishing communication between the entrance chamber and strong room to a lowered position below the same, a door for the shaft entrance resting upon the movable chamber and moving downwardly to a closed position when the movable chamber is lowered, weights slidable in vertical tracks at opposite sides of the shaft entrance, cables connecting the weights and movable chamber and trained over guides above the shaft, doors for the doorway of the entrance chamber slidable from a raised to a closed position, cables extending upwardly from the doors for the entrance chamber and engaged with guides and extending horizontally over the shaft and carrying hooks at their ends, latches to engage said weights and retain the movable chamber in its normal position, keepers engageable by said hooks to retain the doors for the entrance chamber open, plungers extending vertically in said shaft and slidably mounted, a floor for the movable chamber pivotally mounted intermediate its front and rear ends, means to move the plungers upwardly and release the hooks when the floor is tilted in one direction, means to move the latches and release said weights when the floor is tilted in an opposite direction, and means to releasably secure the floor against tilting. 7. In a bank building, an entrance chamber having a doorway, a strong room, a vertical shaft between said entrance chamber and strong room, extending downwardly below the same and having a doorway opening into the entrance chamber, a chamber movable in said shaft from a normal position establishing communication between the entrance chamber and strong room to a lowered position below the same, a door for the shaft entrance resting upon the movable chamber and moving downwardly to a closed position when the movable chamber is lowered, weights slidable in vertical tracks at opposite sides of the shaft entrance, cables connecting the weights and movable chamber and trained over guides above the shaft, doors for the doorway of the entrance chamber slidable from a raised to a closed position, cables extending upwardly from the doors for the entrance chamber and engaged with guides and extending horizontally over the shaft and carrying hooks at their ends, latches to engage said weights and retain the movable chamber in its normal position, troughs extending horizontally above said shaft to guide movements of the last mentioned cables, tubes extending vertically in said shaft and having stops at their upper ends for engagement by said hooks, plungers slidable in said tubes, and means to move the latches and plunger and release the hooks and weights adapted to the weight of a person entering the movable chamber.

for the entrance chamber and engaged with guides and extending horizontally over the shaft and carrying hooks at their ends, latches to engage said weights and retain the movable chamber in its normal position, troughs extending horizontally above said shaft to guide movements of the last mentioned cables, tubes extending vertically in said shaft and having stops at their upper ends for engagement by said hooks, plungers 500
10 slideable in said tubes, the floor of said movable chamber being formed separate from the body portion of the movable chamber and pivoted thereto intermediate its front and rear edges, arms carried by said floor and 105
15 extending beneath the latches and plungers and adapted to move the plungers upwardly to release the hooks when the floor is tilted in one direction and move the latches to release the weights and permit downward 200
20 movement of the movable chamber when the floor is tilted in an opposite direction, and means to releasably secure the floor against tilting.

9. In a bank building, an entrance chamber having a doorway, a strong room, a vertical shaft between said entrance chamber and strong room, extending downwardly below the same and having a doorway opening into the entrance chamber; a chamber movable in said shaft from a normal position establishing communication between the entrance chamber and strong room to a lowered position below the same, a door for the shaft entrance resting upon the movable chamber and moving downwardly to a closed position when the movable chamber is lowered, weights slideable in vertical tracks at opposite sides of the shaft entrance, cables connecting the weights and movable chamber and trained over guides above the shaft, doors for the doorway of the entrance chamber slideable from a raised to a closed position, cables extending upwardly from the doors for the entrance chamber and engaged with guides and extending horizontally over the shaft and carrying hooks at their ends, latches to engage said weights and retain the movable chamber in its normal position, troughs extending horizontally above said shaft to guide movements to the last mentioned cables, tubes extending vertically in said shaft, and having stops at their upper ends for engagement by said hooks, plungers 250
30 slideable in said tubes, the floor of said movable chamber being formed separate from the body portion of the movable chamber and having a fulcrum bar pivoted to opposed walls of the movable chamber and having its ends formed with tongues, securing strips extending vertically in said shaft at opposite sides of said movable chamber and having forks at their lower ends to engage said tongues and retain the floor stationary, means to shift said strips upwardly to release said tongues and permit tilting of the floor when a person enters the movable chamber, and arms carried by said floor and extending beneath the latches and plungers 350
35 and adapted to move the plungers upwardly to release the hooks when the floor is tilted in one direction and move the latches to release the weights and permit downward movement of the movable chamber when the floor is tilted in an opposite direction.

doors and bridge actuated by the weight of a person upon the bridge, and means to render the releasing means inoperative.

12. In a bank building, an entrance chamber, a strong room spaced from the entrance chamber, a bridge movable from a position establishing communication between the entrance chamber and strong room to a lowered position, means to releasably hold the bridge in an operative position, means to release said bridge actuated by weight of a person upon the bridge, and means to render the releasing means inoperative.

In testimony whereof I affix my signature.

15 WILLIAM J. H. RUSCHMEYER.
